CLAIM

The ornamental design for a camp mug, as shown and described.

DESCRIPTION

FIG. 1 is a top perspective view of a camp mug of the invention;

FIG. 2 is a front elevation thereof;

FIG. 3 is a rear elevation thereof;

FIG. 4 is a right side elevation thereof, the left side elevation being a mirror image;

FIG. 5 is a top plan view thereof; and,

FIG. 6 is a bottom plan view thereof.

The portions of the camp mug shown in broken line form no part of the claimed design.

1 Claim, 6 Drawing Sheets
